Attorney.

UNITED STATES PATENT OFFICE.

MILTON F. WILLIAMS, OF ST. LOUIS, MISSOURI, ASSIGNOR TO WILLIAMS PATENT CRUSHER AND PULVERIZER CO., OF ST. LOUIS, MISSOURI, A CORPORATION OF MISSOURI.

METAL-CATCHER FOR GRINDERS.

1,278,542.

Specification of Letters Patent. Patented Sept. 10, 1918.

Application filed June 10, 1918. Serial No. 239,292.

To all whom it may concern:

Be it known that I, MILTON F. WILLIAMS, a citizen of the United States, residing at St. Louis, State of Missouri, have invented certain new and useful Improvements in Metal-Catchers for Grinders, of which the following is a specification.

This invention relates to certain new and useful improvements in metal catchers for 10 grinders and like machines, the peculiarities of which will be hereinafter described and claimed.

The main object of my invention is to provide means for catching metal, gravel 15 and other relatively heavy extraneous matter generally contained in feed supplied to grinders, pulverizers and like machines, and to clear the catcher of the partly ground or light material some of which is also thrown 20 into the catcher by the hammers of the grinder.

In the accompanying drawing on which like reference letters indicate corresponding parts, Figure 1 represents a vertical 25 transverse section of part of a grinder provided with my improved catcher; and Fig. 2 a detail side view and partial section of my metal catcher detached.

A designates the shaft of a grinder of the 30 class described on which are secured disks B supporting hammer rods C on which are pivoted rotary hammers D, operating in the direction of the arrow past the breaker plate E and cage F. G is a supply hopper located above the rotary hammers on a cover H provided with a vertical wall I substantially over the axis of said shaft. A hopper inlet J through the cover is provided with a downwardly inclined slide valve K mounted 35 in suitable grooves in the sides of said inlet, and with its lower inner end k normally adjacent to the said wall I, so as to deliver the feed in a vertically radial stream practically over the center of the shaft, and 40 close to the path of the ends of the hammer.

In the cover casing below the feed slide, and opposite the central wall I, is an opening L that is substantially the width of the casing and has an inclined bottom M, preferably parallel to said slide and with its inner edge N located on the same level as, or a little below, the lower edge i of said central wall I, and likewise of the path of the hammers as they pass said edge i.; that is to 45 say, this outlet opening is substantially tan-

gential to the path of the ends of the hammer as they pass the feed inlet. The upper edge of said breaker plate and its supporting slide O, is directly adjacent to said edge N, and forms an acute angle with the bottom M, so that feed and other matter driven by said hammers out of said opening L will be directed into a box or receptacle adapted to form a closed chamber. This arrangement of the grinder is similar to that shown in 50 Williams' prior Patent No. 1,235,868. In the present case however a box of different style adapted to prevent accumulation of light material in the space reserved for the foreign material, is shown and described, 55 This box has an opening at one side, practically the width of the casing and matching said opening L. The bottom P of said box is preferably inclined and forms an acute angle with the opposite side wall Q by which 60 a converging tapering pocket is formed below the bottom M of said opening L. This bottom is preferably hinged at R by its upper edge to the lower edge of one side, and the lower edge p is adjustable to and from the 65 wall Q, to form a variable width of air opening,—preferably by means of a threaded bolt S passing through said bottom and having a nut on each side by which the 70 width of the opening is regulated. A long 75 narrow air inlet is thus available at the very bottom of said pocket, and the air suction caused by the rotating hammers, or other means, will draw the air through this regulated inlet and the material deposited in the 80 pocket, thereby separating from the heavy particles, the lighter portion of feed that may be driven by the hammers into the box. A wall T opposite the opening L, is nearly 85 normal to the path of the particles driven into said box, and if anything inclined upward toward the hopper from a horizontal plane so as to deflect the impinging particles downward into the pocket. The end edges 90 of the inclined bottom P preferably overlap the end walls U, so that adjustment of the bottom p to form a long narrow air inlet 95 will not admit air likewise at the ends above the deposited material.

The box is closed, except for the opening 100 in the side that matches the outlet opening in the side of the grinder, and except also for the variable sized air inlet slit at the very bottom of the tapering pocket, by which air inlet the proper quantity of air to 105

2
clear the pocket of said light particles is admitted in a thin stream the whole width of the box as required. The heavy extraneous particles, thus freed from light particles, collect in the bottom of the pocket and are removed occasionally as they accumulate, by releasing said inclined bottom. While I am aware that it is not new to provide an opening in the side wall of a rotary beater 10 casing below a feed inlet and tangential to the path of the beaters, yet the provision of a closed box except for the openings as above described, and as shown on the drawings, is believed to be new in the art to 15 which this application pertains.

I claim:

The combination with a machine of the

character described comprising rotary beaters and a casing having a top feed hopper with a slant bottom, and having an adjacent 20 outlet beyond and guarded by said slant bottom from gravitating feed, of a box having in its front wall an opening matching said outlet, and comprising top, back, end walls, and a downwardly inclined bottom,— 25 said bottom being hinged at the top to said back, and having its lower edge adjustable to and from said front wall, and means to secure said bottom in any varied opening at said lower edge, substantially as de- 30 scribed.

In testimony whereof I have affixed my signature.

MILTON F. WILLIAMS.
